CLAIM

The ornamental design for a control panel for fluid distribution equipment as shown and described.

DESCRIPTION

FIG. 1 is a perspective view of a control panel for fluid distribution equipment, showing my new design;

FIG. 2 is a right side view thereof;

FIG. 3 is a left side view thereof;

FIG. 4 is a top view thereof;

FIG. 5 is a bottom view thereof; and,

FIG. 6 is a front view thereof.
